UNITED STATES PATENT OFFICE

ARTHUR H. WATSON, OF CHICAGO, ILLINOIS

TELEVISION APPARATUS

Application filed April 22, 1929. Serial No. 356,944.

This invention relates to improvements in television apparatus and particularly to the scanning mechanism forming the essential part of the apparatus.

5 The present invention is an improvement over that type of apparatus described and illustrated in my co-pending application for patent, Serial No. 345,005, filed March 7, 1929.

An object of the invention is to provide 10 an improved television apparatus.

In the transmission and reception of television pictures today two distinct types of pictures are formed, one consisting of a plurality of substantially straight parallel lines 15 and the other consisting of a plurality of curved parallel lines. This condition is brought about by the employment of apparatus in the first instance including a drum scanning mechanism,—that is, a rotating 20 drum, from which beams of light pass substantially radially to scan the object at the transmitting end and, in the case of the receiving apparatus, to traverse a screen. Such an arrangement of apparatus produces 25 what is known as a straight line picture.

Other types of apparatus incorporate what is known as the circular scanning disc through or from which rays pass or are reflected in a direction substantially parallel with the 30 axis of rotation in both the transmitting and receiving apparatus. The result of this arrangement is the forming of what is known as a curved line picture.

I shall not describe in detail the construction or operation of the drum type scanner or the disc type scanner as this mechanism is well known in the art.

The principal object of my present invention is to incorporate in television apparatus 40 scanning mechanism forming a part of the apparatus which is capable of producing both straight line and curved line pictures at will.

Another object is to provide television apparatus wherein the change from straight 45 line to curved line pictures or vice versa may be accomplished by the mere shifting of position of the scanning mechanism.

Another object is to provide television apparatus which is extremely compact and 50 simple in construction.

Other objects and advantages will be hereinafter set forth in the following description and appended claims.

Apparatus embodying my invention is illustrated in the accompanying drawings 55 forming a part of this application wherein:

Fig. 1 is a vertical sectional view through the apparatus;

Fig. 2 is a front elevation of the apparatus illustrated in Fig. 1;

Fig. 3 is similar to Fig. 1 illustrating the scanning mechanism in its shifted position to produce curved line pictures;

Fig. 4 is a schematic illustration showing the scanning mechanism adjusted for a 65 straight line picture;

Fig. 5 is a schematic illustration similar to Fig. 1 but showing the scanning mechanism set for a curved line picture; and

Fig. 6 is a diagrammatic view illustrating 70 the electrical circuit for controlling the motor and glow lamp.

In general, my improved television apparatus comprises a housing A, a scanning drum B, the construction of which has been particularly set forth in my aforementioned pending application, a motor C for driving the drum, a glow lamp D instantaneously responsive to the output current from a radio receiver arranged so that its light may be reflected from the drum B upon a translucent screen E disposed at the front wall of the housing A, the entire scanning mechanism including the drum B and motor C being shiftable to either of the positions illustrated in 85 Figs. 1 and 3 at will.

The housing A may be constructed of wood or metal and made substantially light-proof with its top wall 10 forming a cover hinged at 11 so as to facilitate access to the interior of the housing. The glow lamp D is mounted in a tube 12 which projects through an annular ring 13 having a rack and pinion adjustably associated therewith for moving the lamp D along its optical axis toward or away from the drum B. This structure permits the focusing of the light spot reflected from the drum upon the screen E. The lamp D may be any type of lamp which is capable of assuming full brilliancy and falling back to total darkness 100

in intervals of time not longer than one-twenty thousandth of a second. For this purpose neon gas glow lamps of the crater type have been widely used. The light produced 5 is highly concentrated so that it may be reproduced on the screen E in substantially the same size and shape.

The scanning drum B is rotatably mounted upon a frame 15 and geared through a speed 10 reduction mechanism enclosed in housing 16 to the motor C. In the present embodiment of the invention I contemplate using a variable speed motor, the speed of which may be controlled by the operator by rheostat 17, 15 the current for which may be turned on and off by manipulation of a switch 18.

Both the motor C and the frame 15 upon which the scanning drum is mounted are carried upon a plate 19 which is secured by bolts 20 and wing nuts 20 to either the bottom wall 21 or the rear wall 22 of the housing A, depending upon the nature of the picture required, i. e., straight line or curved line pictures.

25 The drum B has a plurality of separate concave reflectors 30 mounted thereupon, the number of which determines the number of lines in the picture, each of which is so adjusted as to cause light reflected from the lamp D to traverse the screen E in a succession of substantially parallel lines close enough to one another to illuminate the entire screen when the disc is rotated at a speed of substantially 900 R. P. M. This phenomena 30 is caused by the persistency of vision and is wellknown in television practice.

The concave reflectors 30 comprise optical elements which cause a focusing of the light 40 from the lamp D to a spot such as represented at 32 upon the screen which is virtually an image of the visibly illuminated part of the lamp.

The lamp D is controlled in general by a variable resistance 35 in series therewith so 45 that the operator may increase or decrease the general illumination of the picture.

In operation the output terminals of a radio receiver are connected to the input terminals 36 (see Fig. 6) of the lamp D and the 50 alternating current so conducted to the lamp changes in proportion to the signal strength of the broadcast picture and causes the lamp D to rise and fall in illumination, which constant change in intensity of illumination is 55 perceived upon the screen E as the drum B revolves at substantially 900 R. P. M. or at such speed as is prescribed by the broadcasting station. It should be noted here that the speed and relative position of the drum B 60 must exactly coincide with the similar rotating part of the scanning mechanism at the broadcast station. Hence the rheostat 17.

Assuming that the apparatus is assembled 65 as shown in Fig. 1, and with reference to Fig. 4, it will be seen that the light reflected

from lamp D will be reflected from the reflectors 30 along substantially radial paths with respect to the axis of the drum,—hence the line drawn by the moving spot 32 will be a straight line and as the drum continues to revolve a plurality of straight lines will be so formed to comprise a complete picture, the persistency of vision operating to maintain the picture wholly upon the screen for one revolution of the drum. Upon the next revolution a new picture will be formed.

70 It is important that the scanning apparatus embodying my invention shall be constructed with the concave reflectors 30 set at substantially 45 degrees from the axis of rotation as otherwise a shift from straight line to curved line pictures would be difficult to accomplish.

75 Let us assume now that it is desirous to produce a curve line picture because the broadcasting station in operation at this time is broadcasting with apparatus including a disc type scanner. The operator then will shift the plate 19 bearing the motor and scanning drum to the position shown in Fig. 3 80 and schematically in Fig. 5, at the same time throwing the reversing switch 40 on motor C. The result of this change in assembly will cause light reflected from the lamp D to be projected away from the reflectors 30 on the drum along axes which are substantially concentric with the axis of rotation and a curved line will be produced as the spot 32 traverses screen E.

85 What I claim is new and desire to secure 100 by Letters Patent of the United States is:

1. Television apparatus comprising a source of concentrating light, a screen, a rotatable drum and a plurality of focusing reflectors, said reflectors being so arranged as to reflect and focus said concentrated light upon the screen along axes substantially radial to the axis of the drum when the axis of the direct light beams from said light are perpendicular to the plane of rotation of the drum, whereby a line described by the focused light upon the screen when said drum is rotated is substantially straight.

105 2. Television apparatus comprising a source of concentrated light, a screen, a rotatable drum and a plurality of focusing reflectors carried on said drum, said reflectors being arranged circumferentially about the drum and having their reflecting surfaces inclined at substantially 45 degrees from the axes of the drum, said light source having its optical axis perpendicular to an axis perpendicularly intersecting the center of said screen, both of said axes intersecting in the plane of said reflectors, each of said reflectors beginning with one certain reflector having its angle of inclination slightly less than the next adjacent and succeeding reflector thereby causing the successively described lines 110 upon the screen to lie one beneath the other.

3. In a television apparatus, a rotatable member, a plurality of reflecting surfaces on said member angularly disposed with respect to the axis of rotation thereof, a fixed source of light, a fixed viewing screen and means permitting the shifting of the axis of rotation of said rotatable member to vary the path of light from said light source as it is reflected from said surfaces to said screen to scan in straight or curved lines at will.

10 4. In a television apparatus, a rotatable member, a plurality of reflecting surfaces on said member angularly disposed with respect to the axis of rotation thereof, a source of light, a viewing screen and means for permitting relative movement between said light source and the axis of said rotatable member to vary the path of light from said light source as it is reflected from said surfaces to 20 said screen to scan in straight or curved lines at will.

In witness whereof, I hereunto subscribe my name this 19 day of April, 1929.

ARTHUR H. WATSON.
